UNITED STATES PATENT OFFICE

ALVIN G. SHERMAN, OF GROSSE POINTE, MICHIGAN, ASSIGNOR TO DETROIT VAPOR STOVE COMPANY, OF DETROIT, MICHIGAN, A CORPORATION OF MICHIGAN

DESIGN FOR A HANDLE FOR MOVABLE STOVE PARTS

Application filed March 30, 1931. Serial No. 39,300. Term of patent 7 years.

To all whom it may concern:

Be it known that I, ALVIN G. SHERMAN, a citizen of the United States, residing at 216 Lakeland Avenue, Grosse Pointe, in the county of Wayne and State of Michigan, have invented a new, original, and ornamental Design for a Handle for Movable Stove Parts, of which the following is a specification, reference being made to the accompanying drawings, forming part thereof.

Fig. 1 is a perspective view of the handle, showing my new design.

Fig. 2 is a front elevation thereof.

The handle is used with hinged stove doors, sliding stove drawers, and similar stove parts.

I claim:

The ornamental design for a handle for movable stove parts as shown and described.

ALVIN G. SHERMAN.
